UNITED STATES PATENT OFFICE.

FRED M. PARKS, OF MURRAYSVILLE, AND GEORGE R. SHAW, OF WILKINSBURG, PENNSYLVANIA, ASSIGNEES TO WESTINGHOUSE ELECTRIC AND MANUFACTURING COMPANY, A CORPORATION OF PENNSYLVANIA.

SYSTEM OF CONTROL.

Application filed September 26, 1925. Serial No. 58,807.

Our invention relates to systems of control and it has particular relation to such systems as are employed in connection with rolling mills and the like.

One object of our invention is to provide an improved and simplified system for effecting dynamic braking of a direct-current motor.

Another object of our invention is to prevent an excessive rise in armature voltage during dynamic braking and "drifting" periods.

Other objects of our invention will become apparent from the following description of the operation of the system and from the appended claims.

In accordance with our invention, a single resistor is employed for both the starting and the dynamic-braking operations of the motor, and dynamic braking is effected without other main switching apparatus except the usual single-pole independently-operable magnetic reversing-switches. The accelerating switches, together with current-limit accelerating relays, are employed to obtain "graduated" dynamic braking, as well as to accelerate the motor.

Motors of the type herein employed are commonly adapted for speed control by means of a shunt-field rheostat. The speed range by field control may be of the familiar two-to-one ratio or of a higher ratio. We preferably employ a motor-operated field rheostat with suitable means for controlling the operation of the rheostat motor, as hereinafter more fully described.

Our invention will be best understood by reference to the accompanying drawing, in which Fig. 1 is a diagrammatic representation of main circuits and apparatus embodying our invention,

Fig. 2 is a diagrammatic view of control circuits employed in connection with the system of Fig. 1, and

Fig. 3 is a sequence chart indicating the operation of the main switches.

With reference to the accompanying drawing, a main motor 1 having an armature 2 and a series field-magnet winding 3 is adapted to be connected through a resistor 4 to line conductors 5 and 6. The motor is also provided with a shunt field-magnet winding 7, which is controlled by means of a motor-operated field rheostat 8. In accordance with a familiar practice, the rheostat motor 9, com-

monly termed a pilot motor, is controlled by a plurality of field-magnet windings 10 and 11 that may be selectively energized for forward or reverse operation. These field windings are energized by means of "slow" and "fast" push-buttons or switches 12 and 13, respectively, and the pilot motor circuit is finally interrupted by means of limit switches 14 and 15 that are mechanically operated in accordance with the movement of the rheostat arm 16 in the "weak" field and "full" field positions, respectively, of the rheostat.

A plurality of accelerating switches 21, 22, 23 and 24 are provided for controlling the resistor 4 and these switches are preferably controlled by means of current limit relays 25, 26, 27, 28 and 29 of well-known character. "Forward" and "reverse" push-buttons 31 and 32 are provided for energizing a pair of relays 33 and 34 that respectively control the operating coils 37, 38, 39 and 40 of the forward and reverse switches 41, 42, 43 and 44.

In order to prevent "plugging" the main motor 1, we have employed a pair of relays 45 and 46 each having two operating coils 47 and 48 and 49 and 50, respectively. These relays function in such manner that when the motor is operating in a forward direction, the forward relay 45 occupies its illustrated closed circuit position and the relay 46 becomes energized to deenergize relay 34, for reverse operation, until the counter E. M. F. of the main motor armature has been reduced to a safe value. The coils 47 and 48 of the forward relay 45 are differentially wound so that this relay is inoperative during forward operation: that is, it maintains its closed position. The reverse relay coils 49 and 50 are wound cumulatively with respect to forward operation. Since one coil of each of these relays is connected across the motor armature it will be evident that, when the armature connections are reversed and the motor is operating in the reverse direction, the compounding effect of these coils is exactly the reverse of that described for forward operation. In other words, the reverse relay 46 remains closed and the forward relay 45 opens. Any suitable means may be employed, however, to prevent plugging the motor, which operation in certain classes of service is highly undesirable and is known to cause undue stresses in the motor and mechanical parts of the driven apparatus. A

"stop" button 51 and a no-voltage relay 52 are provided in the control circuit in a customary manner.

Dynamic braking of the motor is effected by means of a brake push-button 53 (Fig. 1) which energizes a relay 54 to maintain the "forward" switch 43 closed and to effect the closure of the reversing switch 42 while the other two reversing switches are inoperative.

10 During dynamic braking, the field rheostat 8 is returned toward the "full" field position and, in order to prevent a too sudden strengthening of the motor field, we have provided a voltage relay 55 having an operating coil 56 connected across the terminals of the motor armature 2. If the armature voltage exceeds a predetermined value, relay 55 momentarily interrupts a circuit through the pilot motor 9, and this relay operation 15 may be repeated during dynamic braking in accordance with voltage conditions, or until normal voltage obtains.

In the accompanying drawing, we have designated the electrical interlocks, in accordance with a familiar practice, as being mechanically connected to, and actuated by, the respective switches. Interlocks marked "In" 20 are closed when the corresponding switches are "in" or closed, and similarly are "out" when the switches are open.

Assuming the apparatus in its illustrated and inoperative condition, with no-voltage relay 52 closed, the main motor 1 is started in a familiar manner by means of the forward push-button 31, to energize relay 33, which closes to establish a circuit for the operating coils 37 and 38 of the independently operable reversing switches 41 and 43. As the motor accelerates, the starting resistor 40 is gradually shunted by means of the automatically controlled accelerating switches 21, 22, 23, and 24, in a familiar manner. The operating coil 49 of reverse relay 46 is of insufficient strength to operate the relay. The other coil 50 of relay 46 is energized in accordance with the armature voltage and is adapted to assist coil 49 as the motor operates in a forward direction. The reversing relay 45, therefore, is now inoperative, as previously explained, and the motor cannot be reversed by operation of the reversing push-button 32 until the brake push-button 53 has first been actuated to effect dynamic braking.

To establish dynamic braking, relay 54 is energized by a circuit extending from the motor armature 2 through resistor 4, brake push-button 53, the interlocks "41-out" and "44-out" and the relay coil 57 to the other side of the motor armature. In order to complete the dynamic braking circuit, the two reversing switches 41 and 43 must be opened by operation of the stop button 51 so that the operating coil 57 of relay 54 may be energized. Upon the closure of relay 54, a circuit is established for the operating coils 38

and 39 of switches 42 and 43, and, upon the closure of these switches, a dynamic braking circuit becomes effective, extending from the motor armature 2 through resistor 4 and reversing switches 43 and 42 to the other side of the armature. The current traversing the motor armature then controls the accelerating relays 25 to 29 in a well-known manner, so that the accelerating switches 21, 22 and 23 may be successively closed, and thereby 75 armature current of a suitable braking value is maintained, as resistor 4 is gradually shunted.

It will be noted that, during the dynamic braking period, accelerating switch 24 is inoperative because interlock 42-out is included in the circuit of its actuating coil, whereas switch 42 is closed at this time.

Referring to Fig. 1 a circuit is established for the pilot motor 9 extending from conductor 5 through relay 55, interlock "24-out", limit switch 14, field winding 10 and the pilot motor armature to conductor 6 whereby the field rheostat 8 is actuated toward the full field position. If the main motor load, during braking, is such that the armature voltage rises above a predetermined value, relay 55 is actuated to interrupt the pilot motor circuit until a proper voltage obtains, when the operation of the pilot motor is continued.

It is sometimes necessary to momentarily operate the main motor to reverse the rolls of a steel mill, for example, and this reverse operation may be effected from standstill, or from low motor speed, by operating the reverse button 32 to energize relay 34, which relay can only be energized when relay 46 is closed, and when the armature voltage has been reduced to a low value. The motor may then be automatically accelerated, in a manner similar to that described for forward operation, by means of the accelerating relays and switches, and the motor may thereafter be disconnected from the line and dynamic braking applied by operation of the 100 brake push button 53 as hereinbefore described.

It should be noted that whereas we have employed the same resistor for both starting and dynamic braking operations, we have 105 not employed additional main switching apparatus, but, in accordance with our invention, we are enabled to utilize the reversing and accelerating switches to accomplish the desired result. In so far as we are aware, this 110 system, as applied to reversing control, is new and its utility will be at once recognized.

Although we have set forth the preferred embodiment of our invention, it will be understood that various modifications thereof 115 may be made without departing from the spirit and scope of the invention. We desire, therefore, that only such limitations shall be imposed thereon as are indicated in the 120 appended claims.

We claim as our invention:

1. The combination with a motor and a resistor therefor, of a pair of independently operable switches for connecting said resistor in circuit for forward operation, a pair of independently operable switches for connecting said resistor in circuit for reverse operation, means for energizing one switch of each of said pairs to establish a dynamic-braking circuit comprising said resistor, and load-responsive means for varying the effective value of said resistor.
2. The combination with a motor and a resistor therefor, of a pair of independently operable switches for connecting said resistor in circuit for forward operation, a pair of independently operable switches for connecting said resistor in circuit for reverse operation, means for energizing one switch of each of said pairs to establish a dynamic-braking circuit comprising said resistor, and load-responsive means for varying the effective

value of said resistor during starting and during dynamic braking.

3. The combination with a motor and a resistor therefor, of a pair of independently operable switches for connecting said resistor in circuit for forward operation, a pair of independently operable switches for connecting said resistor in circuit for reverse operation, means for energizing one switch of each of said pairs to establish a dynamic-braking circuit comprising said resistor, means for insuring the completion of said dynamic braking circuit prior to establishing said reversing connections and load-responsive means for varying the effective value of said main motor during the braking period.

In testimony whereof, we have hereunto subscribed our names this first day of September, 1925.

FRED M. PARKS.
GEORGE R. SHAW.
